Primary Examiner — Kevin Rudzinski(74) *Attorney, Agent, or Firm* — King & Spalding LLP(57) **CLAIM**

The ornamental design for a luminaire, as shown and described.

DESCRIPTION

FIG. 1 is a perspective view of a new ornamental design for a luminaire;

FIG. 2 is a front elevation front view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof; and,

FIG. 8 is a partial rear elevation view thereof.

The broken lines shown represent unclaimed subject matter and form no part of the claimed design.
